UNITED STATES PATENT OFFICE.

JEREMIAH O'MEARA, OF NEW YORK, N. Y.

RHEOSTAT.

SPECIFICATION forming part of Letters Patent No. 447,494, dated March 8, 1891.

Application filed November 15, 1890. Serial No. 371,596. (No model.)

To all whom it may concern:

Be it known that I, JEREMIAH O'MEARA, a citizen of the United States, residing at New York, in the county of New York and State 5 of New York, have invented a certain new and useful Improvement in Rheostats, of which the following is a full, clear, and exact description.

The object of this invention is to furnish a 10 rheostat which may be used in connection with therapeutical electrodes for electro-medical purposes, and which is also adapted for use in connection with electro-magnetic bells for ringing them, and which may be used for 15 the general purposes of a rheostat.

The invention consists in a coil of wire of 20 good conductivity mounted upon a suitable support and provided with a plug for electrical connection with an electric lamp-socket, for example, and adapted to receive electrodes or leading-out wires, whereby to utilize the current, all as I will proceed now more particularly to set forth and finally claim.

In the accompanying drawings, illustrating 25 my invention, in the two figures of which like parts are similarly designated, Figure 1 is an elevation of an apparatus constructed in accordance with my invention, showing in dotted outline an electro-magnetic bell; and Fig. 30 2 is a cross-section on line $x-x$ of Fig. 1.

Without intending thereby to limit my invention to the mere details of construction, I will proceed to describe my invention by reference to the aforesaid accompanying drawings.

In the said drawings, a may represent an insulating-support having the end kerfs b .

c is a wire of good electrical conductivity, secured to the board by winding or coiling it 40 about the said board through the kerfs b .

The support a and its coil of wire constitute what I designate here the "rheostat." This rheostat is supplied with the electric current from an electric-light circuit by means 45 of conductors d , secured to binding-posts e on the support, and which binding-posts also receive opposite ends of the wire c . The conductors d for convenience may be insulated and twisted together, as at f , and 50 united in and secured to a plug g . This plug g is adapted to be connected electrically with the socket h of any ordinary electric-light

lamp, and thereby to convey the electric-light current to the rheostat. In the leading-in circuit-wires i safety-plugs j of approved construction are placed to prevent the burning out of the instrument or apparatus in case of grounding or other accident. The lamp-socket h and its key or cut-out l may be as usual.

At one end of the rheostat there are binding posts or hooks 1, 2, 3, 4, 5, 6, 7, and 8 or any other desired number. For example, instead of having the hooks or binding-posts, as shown, there may be half as many such 65 hooks or binding-posts as there are lengths of wire on one side of the support a , so that there shall be two lengths of wire for each. Now by connecting the object to be electrically charged with the lowermost hook or binding-post by one wire and connecting the other wire with one of the other hooks or binding-posts a current of greater or less strength, in accordance with the number of coils included between the electrodes, will be transmitted 70 through such electrodes or conductors to the object. In the present instance I have shown wires m and n respectively terminating in hooks or eyes m' and n' to engage the binding-posts 1 to 8. These wires m and n are 75 connected with sponge-holders o and p , which are the electrodes for use in administering the electricity therapeutically, and for convenience I have selected for illustration the sponge-holders shown in the expired Patent 85 No. 116,197, dated June 20, 1871.

Instead of having therapeutical electrodes, I may use leading-out wires suitable for the purpose, to which the rheostat is to be applied.

The apparatus may be provided with any convenient device for testing the strength of the current. One such device I have shown in dotted outline in the drawings, and it consists of an electro-magnetic bell q , having 95 wires r and s , which are provided with suitable means for connection with the hooks or binding-posts 1 to 8. By applying these wires r and s to the binding-posts and noting the loudness of the ringing of the bell the strength 100 of the current may be ascertained with sufficient nearness for all practical purposes. Other testing devices might be employed.

I may use this rheostat for ringing one or

more electro-magnetic bells, and the foregoing description of the manner of applying an electro-magnetic bell to the rheostat as a testing device will serve to illustrate the manner of ringing such bells for alarm or signaling purposes.

The support *a* may be provided with hooks or eyes *t* for suspending it in position for use, although in the case of the use of the device 10 for therapeutic purposes I propose to supply the device with a case or cover or box, in which the respective parts may be conveniently inclosed for transportation and use. The current is obtained by connecting the 15 plug *g* with the electric-light lamp-socket in usual manner.

Obviously, if an electric-light circuit be not available, the rheostat may receive its current from other sources, and, indeed, a battery 20 may be included in its leading-in or leading-out wires for increasing or modifying the current at pleasure.

What I claim is—

1. A support and an electrical conductor 25 coiled about it, a series of binding-posts disposed at intervals along said support and in contact with the conductor, leading-in wires

connected to opposite ends of said conductor and adapted to be connected with an electric-light circuit or other source of electricity, 30 and leading-out wires, one of which is movable to include a greater or less number of coils of the conductor, substantially as and for the purpose described.

2. A support and an electrical conductor 35 coiled about it, a series of binding-posts disposed at intervals along said support and in contact with the conductor, leading-in wires connected to opposite ends of said conductor and adapted to be connected with a source of 40 electricity, such as an electric-light circuit, leading-out wires, one of which is movable to include a greater or less number of coils of the conductor, and means, such as therapeutic electrodes or bells, included in the 45 circuit of the leading-out wires, substantially as and for the purpose described.

In testimony whereof I have hereunto set my hand this 14th day of November, A. D. 1890.

JEREMIAH O'MEARA.
